UNITED STATES PATENT OFFICE

143,616

DESIGN FOR A TOY HELICOPTER

Eoina Nudelman, Chicago, Ill.

Application August 2, 1945, Serial No. 121,171

Term of patent 7 years

(CL. D34—15)

To all whom it may concern:

Be it known that I, Eoina Nudelman, a citizen of France, residing at Chicago, in the county of Cook and State of Illinois, have invented a new, original, and ornamental Design for Toy Helicopters, of which the following is a specification, reference being had to the accompanying drawing, forming part thereof.

Fig. 1 is a top plan view of a toy helicopter, showing my new design;

Fig. 2 is a side elevational view; and
Fig. 3 is a front elevational view.

I claim:

The ornamental design for a toy helicopter, as shown.

EOINA NUDELMAN.
